UNITED STATES PATENT OFFICE.

GEORGE W. REAM, OF CANTON, OHIO, ASSIGNOR TO THE BUCHER & GIBBS PLOW COMPANY, OF SAME PLACE.

DESIGN FOR A SHOE FOR PLOWS.

SPECIFICATION forming part of Design No. 32,126, dated January 23, 1900.

Application filed December 2, 1899. Serial No. 739,052. Term of patent 14 years.

To all whom it may concern:

Be it known that I, GEORGE W. REAM, a citizen of the United States, residing at Canton, in the county of Stark and State of Ohio, have 5 invented and produced a new and original Design for a Shoe for Plows, of which the following is a specification.

In the accompanying drawings, Figure 1 is an elevation of a shoe embodying my invention. Fig. 2 is a view looking down upon the top edge. Fig. 3 is a view of the side opposite to that shown in Fig. 1.

My invention is a new design of a part of a plow known as a "shoe" and is adapted to support and be connected to the landside. The design resides in the shape and the surface configuration of the inside face, the outside face being plain and flat throughout. As shown, the shoe is made with parallel upper 15 and lower edges, as at *a b*. At the rear end these edges are connected by a curved end *c*.

At the front end the lower corner is square, as at *d*, while the upper corner is rounded, as at *e*. On the inner face of the shoe, extending along about the rear half of the lower edge, 25 is a flange *f* of increasing thickness from the point *g* to the point *h*, the flange following partly the curved end of the shoe. As shown in Fig. 2, this flange also increases in width from *g* to *i*, from which latter point the outer 30 edge of the flange is substantially parallel with the face of the shoe. Both sides of the shoe are flat throughout forward of the point *g* of the flange.

I claim—

The design for a plow-shoe as herein shown and described.

GEORGE W. REAM.
